UNITED STATES PATENT OFFICE

142,320

DESIGN FOR AN INCINERATOR

Arthur A. Helwig, Chicago, Ill.

Application December 18, 1944, Serial No. 116,975

Term of patent 3½ years

(Cl. D81—1)

To all whom it may concern:

Be it known that I, Arthur A. Helwig, a citizen of the United States, residing at Chicago, in the county of Cook and State of Illinois, have invented a new, original, and ornamental Design for an Incinerator, of which the following is a specification, reference being had to the accompanying drawing, forming part thereof.

The figure is a perspective view of an incinera-

tor showing my new design. The back and other side of the incinerator which are not shown in the drawing are, in appearance, like the front (without the hood or door) and side shown.

I claim:

The ornamental design for an incinerator, as shown and described.

ARTHUR A. HELWIG.
